APPARATUS AND A PROCESS FOR THE RECOVERY OF GASOLINE FROM CRACKED PETROLEUM HYDROCARBONS

Dale F. Babcock, Wilmington, Del., assignor to E. I. du Pont de Nemours & Company, Wilmington, Del., a corporation of Delaware

Application October 14, 1937, Serial No. 168,891

2 Claims. (Cl. 62—122)

This invention relates to a process for the separation of mixtures of gaseous hydrocarbons by liquefaction and fractionation, and more particularly to the recovery of hydrocarbons containing in excess of three carbon atoms per molecule from a complex gas mixture.

The pyrolysis of petroleum materials, as practiced in commercial vapor phase cracking operations, produces both liquid and gaseous products.

10 These cracked gases are usually saturated with materials boiling in the gaseous range which must be recovered prior to use of the gas in other processes or for fuel.

In the gasoline refining industry this recovery 15 of gasoline is often effected by compressing the cracking gas to a moderate pressure, cooling and thereby liquefying a portion of its gasoline content. The uncondensed gases, still under pressure, are then forced up through a scrubbing 20 tower, countercurrent to a light oil which scrubs the remaining gasoline from the fixed gases. The low-boiling gasoline is then distilled from the "fat" oil, which is then recycled to the scrubbing operation. The distillate is joined with the liquid 25 fraction separated after compression, and the mixture is introduced into a stabilizing column where the low-boiling components which are too volatile to be used in gasoline are distilled off. I have found it much more expedient to recover 30 and to stabilize the gasoline content of the cracked gas in a different manner.

One object of this invention is to provide a simple and efficient process whereby the components of a complex mixture of gaseous hydrocarbons, which are usually a stable liquid at ordinary 35 conditions of temperature and pressure, are recovered from the gas mixture. Another object is to provide a method for the recovery of a relatively non-volatile liquid product such as gasoline, free from such constituents as hydrogen, methane, ethane, ethylene, and propylene from a mixture of hydrocarbon gases produced by cracking petroleum products. Still another object is the separation of the gasoline fraction from a 40 mixture of gases obtained by cracking petroleum products. A further object is the provision of an apparatus for the accomplishment of the above ends. Other objects will appear hereinafter.

These objects are accomplished by the following 45 invention which comprises compressing the gas mixture, cooling and separating the liquid formed, which comprises principally gasoline, rectifying the liquid fraction so that the more volatile gases are separated from the materials 50 boiling in the gasoline range, combining the gaseous fraction from the gas and liquid separation step with the gaseous fraction from the rectification step, and further compressing same to a higher pressure, cooling the thus compressed 55 gases and rectifying the resultant fluid so as to

separate all of the fraction boiling within the gasoline range as a liquid and the more volatile components as a gas, reducing the pressure on this second liquid fraction to the pressure of the first part of the system and combining the resulting fluid with the effluent from the first compression step.

The accompanying drawings represent diagrammatically complete apparatuses for the separation of the components of this fluid mixture. 10 Figure I is the simplest modification of the apparatus and embodies a process which has but two compression stages. Figure II is a modification of the apparatus in which three compression stages are used. It is understood that the details of this apparatus, which are well known to those skilled in the art, have been omitted for the sake of clarity and that modifications in the details of construction and in arrangement of parts may be made without departing from the 15 spirit of the invention. The following represents a description of the processes and apparatuses shown in the two figures of the drawings.

In the modification represented by Figure I the crude gas enters the first stage of compressor 4 via conduit 2 under substantially atmospheric pressure. The gas is compressed to about 6 atmospheres and passes to water cooler 8 and separator 12 via conduits 6 and 10. The condensed liquid is passed by gravity flow from separator 12 through conduit 14 into the middle of rectifying column 16. Reflux is provided in this column by heating calandria 42 with steam and cooling condenser 44 with water. The stabilized gasoline produced at the base of rectifier 16 is removed from the system by way of conduit 46 and valve 48. The non-condensable vapors leaving the top of rectifier 16 are combined with the vapor leaving separator 12 and passes to compressor 22 via conduit 20. The gaseous fractions 25 from the separator 12 are combined with the non-condensable vapors from the rectifier 16 by introducing via conduit 18 into conduit 20. These vapors are compressed to 33 atmospheres, cooled to room temperature by means of water 30 cooler 26 and pass to rectifier 30 via conduit 28. Reflux is produced in this rectifier by heating calandria 32 with steam and cooling condenser 38 with water. The non-condensable gas leaving the top of rectifier 30 via conduit 40 passes 35 to a low temperature separation system where pure ethylene and propylene are recovered. The liquid from the base of rectifier 30 is expanded through valve 34 and conduit 36 into conduit 6 where it mixes with the vapors leaving compressor 4. 40

In Figure II the crude gas enters the first stage of compressor 104 by conduit 102, the gas is compressed to about 3 atmospheres and passes to water cooler 108 and separator 112 via conduits 106 and 110. The liquid from the base of separator 112 passes to water cooler 122 and separator 124 via conduits 114 and 116. The liquid from the base of separator 124 passes to water cooler 128 and separator 130 via conduits 126 and 128. The liquid from the base of separator 130 passes to water cooler 134 and separator 136 via conduits 132 and 134. The liquid from the base of separator 136 passes to water cooler 140 and separator 142 via conduits 138 and 140. The liquid from the base of separator 142 passes to water cooler 146 and separator 148 via conduits 144 and 146. The liquid from the base of separator 148 passes to water cooler 152 and separator 154 via conduits 150 and 152. The liquid from the base of separator 154 passes to water cooler 158 and separator 160 via conduits 156 and 158. The liquid from the base of separator 160 passes to water cooler 164 and separator 166 via conduits 162 and 164. The liquid from the base of separator 166 passes to water cooler 170 and separator 172 via conduits 168 and 170. The liquid from the base of separator 172 passes to water cooler 176 and separator 178 via conduits 174 and 176. The liquid from the base of separator 178 passes to water cooler 182 and separator 184 via conduits 180 and 182. The liquid from the base of separator 184 passes to water cooler 188 and separator 190 via conduits 186 and 188. The liquid from the base of separator 190 passes to water cooler 196 and separator 198 via conduits 194 and 196. The liquid from the base of separator 198 passes to water cooler 202 and separator 204 via conduits 196 and 202. The liquid from the base of separator 204 passes to water cooler 208 and separator 210 via conduits 206 and 208. The liquid from the base of separator 210 passes to water cooler 216 and separator 218 via conduits 214 and 216. The liquid from the base of separator 218 passes to water cooler 222 and separator 224 via conduits 220 and 222. The liquid from the base of separator 224 passes to water cooler 228 and separator 230 via conduits 226 and 228. The liquid from the base of separator 230 passes to water cooler 236 and separator 238 via conduits 234 and 236. The liquid from the base of separator 238 passes to water cooler 242 and separator 244 via conduits 240 and 242. The liquid from the base of separator 244 passes to water cooler 248 and separator 250 via conduits 246 and 248. The liquid from the base of separator 250 passes to water cooler 256 and separator 258 via conduits 254 and 256. The liquid from the base of separator 258 passes to water cooler 262 and separator 264 via conduits 260 and 262. The liquid from the base of separator 264 passes to water cooler 268 and separator 270 via conduits 266 and 268. The liquid from the base of separator 270 passes to water cooler 276 and separator 278 via conduits 274 and 276. The liquid from the base of separator 278 passes to water cooler 282 and separator 284 via conduits 280 and 282. The liquid from the base of separator 284 passes to water cooler 288 and separator 290 via conduits 286 and 288. The liquid from the base of separator 290 passes to water cooler 296 and separator 298 via conduits 294 and 296. The liquid from the base of separator 298 passes to water cooler 302 and separator 304 via conduits 300 and 302. The liquid from the base of separator 304 passes to water cooler 308 and separator 310 via conduits 306 and 308. The liquid from the base of separator 310 passes to water cooler 316 and separator 318 via conduits 314 and 316. The liquid from the base of separator 318 passes to water cooler 322 and separator 324 via conduits 320 and 322. The liquid from the base of separator 324 passes to water cooler 328 and separator 330 via conduits 326 and 328. The liquid from the base of separator 330 passes to water cooler 336 and separator 338 via conduits 334 and 336. The liquid from the base of separator 338 passes to water cooler 342 and separator 344 via conduits 340 and 342. The liquid from the base of separator 344 passes to water cooler 348 and separator 350 via conduits 346 and 348. The liquid from the base of separator 350 passes to water cooler 356 and separator 358 via conduits 354 and 356. The liquid from the base of separator 358 passes to water cooler 362 and separator 364 via conduits 360 and 362. The liquid from the base of separator 364 passes to water cooler 368 and separator 370 via conduits 366 and 368. The liquid from the base of separator 370 passes to water cooler 376 and separator 378 via conduits 374 and 376. The liquid from the base of separator 378 passes to water cooler 382 and separator 384 via conduits 380 and 382. The liquid from the base of separator 384 passes to water cooler 388 and separator 390 via conduits 392 and 394. The liquid from the base of separator 390 passes to water cooler 396 and separator 398 via conduits 396 and 400. The liquid from the base of separator 398 passes to water cooler 402 and separator 404 via conduits 406 and 408. The liquid from the base of separator 404 passes to water cooler 412 and separator 414 via conduits 416 and 418. The liquid from the base of separator 414 passes to water cooler 422 and separator 424 via conduits 426 and 428. The liquid from the base of separator 424 passes to water cooler 432 and separator 434 via conduits 436 and 438. The liquid from the base of separator 434 passes to water cooler 442 and separator 444 via conduits 446 and 448. The liquid from the base of separator 444 passes to water cooler 452 and separator 454 via conduits 456 and 458. The liquid from the base of separator 454 passes to water cooler 462 and separator 464 via conduits 466 and 468. The liquid from the base of separator 464 passes to water cooler 472 and separator 474 via conduits 476 and 478. The liquid from the base of separator 474 passes to water cooler 482 and separator 484 via conduits 486 and 488. The liquid from the base of separator 484 passes to water cooler 492 and separator 494 via conduits 496 and 500. The liquid from the base of separator 494 passes to water cooler 502 and separator 504 via conduits 506 and 508. The liquid from the base of separator 504 passes to water cooler 512 and separator 514 via conduits 516 and 518. The liquid from the base of separator 514 passes to water cooler 522 and separator 524 via conduits 526 and 528. The liquid from the base of separator 524 passes to water cooler 532 and separator 534 via conduits 536 and 538. The liquid from the base of separator 534 passes to water cooler 542 and separator 544 via conduits 546 and 548. The liquid from the base of separator 544 passes to water cooler 552 and separator 554 via conduits 556 and 558. The liquid from the base of separator 554 passes to water cooler 562 and separator 564 via conduits 566 and 568. The liquid from the base of separator 564 passes to water cooler 572 and separator 574 via conduits 576 and 578. The liquid from the base of separator 574 passes to water cooler 582 and separator 584 via conduits 586 and 588. The liquid from the base of separator 584 passes to water cooler 592 and separator 594 via conduits 596 and 598. The liquid from the base of separator 594 passes to water cooler 602 and separator 604 via conduits 606 and 608. The liquid from the base of separator 604 passes to water cooler 612 and separator 614 via conduits 616 and 618. The liquid from the base of separator 614 passes to water cooler 622 and separator 624 via conduits 626 and 628. The liquid from the base of separator 624 passes to water cooler 632 and separator 634 via conduits 636 and 638. The liquid from the base of separator 634 passes to water cooler 642 and separator 644 via conduits 646 and 648. The liquid from the base of separator 644 passes to water cooler 652 and separator 654 via conduits 656 and 658. The liquid from the base of separator 654 passes to water cooler 662 and separator 664 via conduits 666 and 668. The liquid from the base of separator 664 passes to water cooler 672 and separator 674 via conduits 676 and 678. The liquid from the base of separator 674 passes to water cooler 682 and separator 684 via conduits 686 and 688. The liquid from the base of separator 684 passes to water cooler 692 and separator 694 via conduits 696 and 698. The liquid from the base of separator 694 passes to water cooler 702 and separator 704 via conduits 706 and 708. The liquid from the base of separator 704 passes to water cooler 712 and separator 714 via conduits 716 and 718. The liquid from the base of separator 714 passes to water cooler 722 and separator 724 via conduits 726 and 728. The liquid from the base of separator 724 passes to water cooler 732 and separator 734 via conduits 736 and 738. The liquid from the base of separator 734 passes to water cooler 742 and separator 744 via conduits 746 and 748. The liquid from the base of separator 744 passes to water cooler 752 and separator 754 via conduits 756 and 758. The liquid from the base of separator 754 passes to water cooler 762 and separator 764 via conduits 766 and 768. The liquid from the base of separator 764 passes to water cooler 772 and separator 774 via conduits 776 and 778. The liquid from the base of separator 774 passes to water cooler 782 and separator 784 via conduits 786 and 788. The liquid from the base of separator 784 passes to water cooler 792 and separator 794 via conduits 796 and 798. The liquid from the base of separator 794 passes to water cooler 802 and separator 804 via conduits 806 and 808. The liquid from the base of separator 804 passes to water cooler 812 and separator 814 via conduits 816 and 818. The liquid from the base of separator 814 passes to water cooler 822 and separator 824 via conduits 826 and 828. The liquid from the base of separator 824 passes to water cooler 832 and separator 834 via conduits 836 and 838. The liquid from the base of separator 834 passes to water cooler 842 and separator 844 via conduits 846 and 848. The liquid from the base of separator 844 passes to water cooler 852 and separator 854 via conduits 856 and 858. The liquid from the base of separator 854 passes to water cooler 862 and separator 864 via conduits 866 and 868. The liquid from the base of separator 864 passes to water cooler 872 and separator 874 via conduits 876 and 878. The liquid from the base of separator 874 passes to water cooler 882 and separator 884 via conduits 886 and 888. The liquid from the base of separator 884 passes to water cooler 892 and separator 894 via conduits 896 and 900. The liquid from the base of separator 894 passes to water cooler 902 and separator 904 via conduits 906 and 908. The liquid from the base of separator 904 passes to water cooler 912 and separator 914 via conduits 916 and 918. The liquid from the base of separator 914 passes to water cooler 922 and separator 924 via conduits 926 and 928. The liquid from the base of separator 924 passes to water cooler 932 and separator 934 via conduits 936 and 938. The liquid from the base of separator 934 passes to water cooler 942 and separator 944 via conduits 946 and 948. The liquid from the base of separator 944 passes to water cooler 952 and separator 954 via conduits 956 and 958. The liquid from the base of separator 954 passes to water cooler 962 and separator 964 via conduits 966 and 968. The liquid from the base of separator 964 passes to water cooler 972 and separator 974 via conduits 976 and 978. The liquid from the base of separator 974 passes to water cooler 982 and separator 984 via conduits 986 and 988. The liquid from the base of separator 984 passes to water cooler 992 and separator 994 via conduits 996 and 998. The liquid from the base of separator 994 passes to water cooler 1002 and separator 1004 via conduits 1006 and 1008. The liquid from the base of separator 1004 passes to water cooler 1012 and separator 1014 via conduits 1016 and 1018. The liquid from the base of separator 1014 passes to water cooler 1022 and separator 1024 via conduits 1026 and 1028. The liquid from the base of separator 1024 passes to water cooler 1032 and separator 1034 via conduits 1036 and 1038. The liquid from the base of separator 1034 passes to water cooler 1042 and separator 1044 via conduits 1046 and 1048. The liquid from the base of separator 1044 passes to water cooler 1052 and separator 1054 via conduits 1056 and 1058. The liquid from the base of separator 1054 passes to water cooler 1062 and separator 1064 via conduits 1066 and 1068. The liquid from the base of separator 1064 passes to water cooler 1072 and separator 1074 via conduits 1076 and 1078. The liquid from the base of separator 1074 passes to water cooler 1082 and separator 1084 via conduits 1086 and 1088. The liquid from the base of separator 1084 passes to water cooler 1092 and separator 1094 via conduits 1096 and 1098. The liquid from the base of separator 1094 passes to water cooler 1102 and separator 1104 via conduits 1106 and 1108. The liquid from the base of separator 1104 passes to water cooler 1112 and separator 1114 via conduits 1116 and 1118. The liquid from the base of separator 1114 passes to water cooler 1122 and separator 1124 via conduits 1126 and 1128. The liquid from the base of separator 1124 passes to water cooler 1132 and separator 1134 via conduits 1136 and 1138. The liquid from the base of separator 1134 passes to water cooler 1142 and separator 1144 via conduits 1146 and 1148. The liquid from the base of separator 1144 passes to water cooler 1152 and separator 1154 via conduits 1156 and 1158. The liquid from the base of separator 1154 passes to water cooler 1162 and separator 1164 via conduits 1166 and 1168. The liquid from the base of separator 1164 passes to water cooler 1172 and separator 1174 via conduits 1176 and 1178. The liquid from the base of separator 1174 passes to water cooler 1182 and separator 1184 via conduits 1186 and 1188. The liquid from the base of separator 1184 passes to water cooler 1192 and separator 1194 via conduits 1196 and 1198. The liquid from the base of separator 1194 passes to water cooler 1202 and separator 1204 via conduits 1206 and 1208. The liquid from the base of separator 1204 passes to water cooler 1212 and separator 1214 via conduits 1216 and 1218. The liquid from the base of separator 1214 passes to water cooler 1222 and separator 1224 via conduits 1226 and 1228. The liquid from the base of separator 1224 passes to water cooler 1232 and separator 1234 via conduits 1236 and 1238. The liquid from the base of separator 1234 passes to water cooler 1242 and separator 1244 via conduits 1246 and 1248. The liquid from the base of separator 1244 passes to water cooler 1252 and separator 1254 via conduits 1256 and 1258. The liquid from the base of separator 1254 passes to water cooler 1262 and separator 1264 via conduits 1266 and 1268. The liquid from the base of separator 1264 passes to water cooler 1272 and separator 1274 via conduits 1276 and 1278. The liquid from the base of separator 1274 passes to water cooler 1282 and separator 1284 via conduits 1286 and 1288. The liquid from the base of separator 1284 passes to water cooler 1292 and separator 1294 via conduits 1296 and 1298. The liquid from the base of separator 1294 passes to water cooler 1302 and separator 1304 via conduits 1306 and 1308. The liquid from the base of separator 1304 passes to water cooler 1312 and separator 1314 via conduits 1316 and 1318. The liquid from the base of separator 1314 passes to water cooler 1322 and separator 1324 via conduits 1326 and 1328. The liquid from the base of separator 1324 passes to water cooler 1332 and separator 1334 via conduits 1336 and 1338. The liquid from the base of separator 1334 passes to water cooler 1342 and separator 1344 via conduits 1346 and 1348. The liquid from the base of separator 1344 passes to water cooler 1352 and separator 1354 via conduits 1356 and 1358. The liquid from the base of separator 1354 passes to water cooler 1362 and separator 1364 via conduits 1366 and 1368. The liquid from the base of separator 1364 passes to water cooler 1372 and separator 1374 via conduits 1376 and 1378. The liquid from the base of separator 1374 passes to water cooler 1382 and separator 1384 via conduits 1386 and 1388. The liquid from the base of separator 1384 passes to water cooler 1392 and separator 1394 via conduits 1396 and 1398. The liquid from the base of separator 1394 passes to water cooler 1402 and separator 1404 via conduits 1406 and 1408. The liquid from the base of separator 1404 passes to water cooler 1412 and separator 1414 via conduits 1416 and 1418. The liquid from the base of separator 1414 passes to water cooler 1422 and separator 1424 via conduits 1426 and 1428. The liquid from the base of separator 1424 passes to water cooler 1432 and separator 1434 via conduits 1436 and 1438. The liquid from the base of separator 1434 passes to water cooler 1442 and separator 1444 via conduits 1446 and 1448. The liquid from the base of separator 1444 passes to water cooler 1452 and separator 1454 via conduits 1456 and 1458. The liquid from the base of separator 1454 passes to water cooler 1462 and separator 1464 via conduits 1466 and 1468. The liquid from the base of separator 1464 passes to water cooler 1472 and separator 1474 via conduits 1476 and 1478. The liquid from the base of separator 1474 passes to water cooler 1482 and separator 1484 via conduits 1486 and 1488. The liquid from the base of separator 1484 passes to water cooler 1492 and separator 1494 via conduits 1496 and 1498. The liquid from the base of separator 1494 passes to water cooler 1502 and separator 1504 via conduits 1506 and 1508. The liquid from the base of separator 1504 passes to water cooler 1512 and separator 1514 via conduits 1516 and 1518. The liquid from the base of separator 1514 passes to water cooler 1522 and separator 1524 via conduits 1526 and 1528. The liquid from the base of separator 1524 passes to water cooler 1532 and separator 1534 via conduits 1536 and 1538. The liquid from the base of separator 1534 passes to water cooler 1542 and separator 1544 via conduits 1546 and 1548. The liquid from the base of separator 1544 passes to water cooler 1552 and separator 1554 via conduits 1556 and 1558. The liquid from the base of separator 1554 passes to water cooler 1562 and separator 1564 via conduits 1566 and 1568. The liquid from the base of separator 1564 passes to water cooler 1572 and separator 1574 via conduits 1576 and 1578. The liquid from the base of separator 1574 passes to water cooler 1582 and separator 1584 via conduits 1586 and 1588. The liquid from the base of separator 1584 passes to water cooler 1592 and separator 1594 via conduits 1596 and 1598. The liquid from the base of separator 1594 passes to water cooler 1602 and separator 1604 via conduits 1606 and 1608. The liquid from the base of separator 1604 passes to water cooler 1612 and separator 1614 via conduits 1616 and 1618. The liquid from the base of separator 1614 passes to water cooler 1622 and separator 1624 via conduits 1626 and 1628. The liquid from the base of separator 1624 passes to water cooler 1632 and separator 1634 via conduits 1636 and 1638. The liquid from the base of separator 1634 passes to water cooler 1642 and separator 1644 via conduits 1646 and 1648. The liquid from the base of separator 1644 passes to water cooler 1652 and separator 1654 via conduits 1656 and 1658. The liquid from the base of separator 1654 passes to water cooler 1662 and separator 1664 via conduits 1666 and 1668. The liquid from the base of separator 1664 passes to water cooler 1672 and separator 1674 via conduits 1676 and 1678. The liquid from the base of separator 1674 passes to water cooler 1682 and separator 1684 via conduits 1686 and 1688. The liquid from the base of separator 1684 passes to water cooler 1692 and separator 1694 via conduits 1696 and 1698. The liquid from the base of separator 1694 passes to water cooler 1702 and separator 1704 via conduits 1706 and 1708. The liquid from the base of separator 1704 passes to water cooler 1712 and separator 1714 via conduits 1716 and 1718. The liquid from the base of separator 1714 passes to water cooler 1722 and separator 1724 via conduits 1726 and 1728. The liquid from the base of separator 1724 passes to water cooler 1732 and separator 1734 via conduits 1736 and 1738. The liquid from the base of separator 1734 passes to water cooler 1742 and separator 1744 via conduits 1746 and 1748. The liquid from the base of separator 1744 passes to water cooler 1752 and separator 1754 via conduits 1756 and 1758. The liquid from the base of separator 1754 passes to water cooler 1762 and separator 1764 via conduits 1766 and 1768. The liquid from the base of separator 1764 passes to water cooler 1772 and separator 1774 via conduits 1776 and 1778. The liquid from the base of separator 1774 passes to water cooler 1782 and separator 1784 via conduits 1786 and 1788. The liquid from the base of separator 1784 passes to water cooler 1792 and separator 1794 via conduits 1796 and 1798. The liquid from the base of separator 1794 passes to water cooler 1802 and separator 1804 via conduits 1806 and 1808. The liquid from the base of separator 1804 passes to water cooler 1812 and separator 1814 via conduits 1816 and 1818. The liquid from the base of separator 1814 passes to water cooler 1822 and separator 1824 via conduits 1826 and 1828. The liquid from the base of separator 1824 passes to water cooler 1832 and separator 1834 via conduits 1836 and 1838. The liquid from the base of separator 1834 passes to water cooler 1842 and separator 1844 via conduits 1846 and 1848. The liquid from the base of separator 1844 passes to water cooler 1852 and separator 1854 via conduits 1856 and 1858. The liquid from the base of separator 1854 passes to water cooler 1862 and separator 1864 via conduits 1866 and 1868. The liquid from the base of separator 1864 passes to water cooler 1872 and separator 1874 via conduits 1876 and 1878. The liquid from the base of separator 1874 passes to water cooler 1882 and separator 1884 via conduits 1886 and 1888. The liquid from the base of separator 1884 passes to water cooler 1892 and separator 1894 via conduits 1896 and 1898. The liquid from the base of separator 1894 passes to water cooler 1902 and separator 1904 via conduits 1906 and 1908. The liquid from the base of separator 1904 passes to water cooler 1912 and separator 1914 via conduits 1916 and 1918. The liquid from the base of separator 1914 passes to water cooler 1922 and separator 1924 via conduits 1926 and 1928. The liquid from the base of separator 1924 passes to water cooler 1932 and separator 1934 via conduits 1936 and 1938. The liquid from the base of separator 1934 passes to water cooler 1942 and separator 1944 via conduits 1946 and 1948. The liquid from the base of separator 1944 passes to water cooler 1952 and separator 1954 via conduits 1956 and 1958. The liquid from the base of separator 1954 passes to water cooler 1962 and separator 1964 via conduits 1966 and 1968. The liquid from the base of separator 1964 passes to water cooler 1972 and separator 1974 via conduits 1976 and 1978. The liquid from the base of separator 1974 passes to water cooler 1982 and separator 1984 via conduits 1986 and 1988. The liquid from the base of separator 1984 passes to water cooler 1992 and separator 1994 via conduits 1996 and 1998. The liquid from the base of separator 1994 passes to water cooler 2002 and separator 2004 via conduits 2006 and 2008. The liquid from the base of separator 2004 passes to water cooler 2012 and separator 2014 via conduits 2016 and 2018. The liquid from the base of separator 2014 passes to water cooler 2022 and separator 2024 via conduits 2026 and 2028. The liquid from the base of separator 2024 passes to water cooler 2032 and separator 2034 via conduits 2036 and 2038. The liquid from the base of separator 2034 passes to water cooler 2042 and separator 2044 via conduits 2046 and 2048. The liquid from the base of separator 2044 passes to water cooler 2052 and separator 2054 via conduits 2056 and 2058. The liquid from the base of separator 2054 passes to water cooler 2062 and separator 2064 via conduits 2066 and 2068. The liquid from the base of separator 2064 passes to water cooler 2072 and separator 2074 via conduits 2076 and 2078. The liquid from the base of separator 2074 passes to water cooler 2082 and separator 2084 via conduits 2086 and 2088. The liquid from the base of separator 2084 passes to water cooler 2092 and separator 2094 via conduits 2096 and 2098. The liquid from the base of separator 2094 passes to water cooler 2102 and separator 2014 via conduits 2106 and 2108. The liquid from the base of separator 2014 passes to water cooler 2112 and separator 2114 via conduits 2116 and 2118. The liquid from the base of separator 2114 passes to water cooler 2122 and separator 2124 via conduits 2126 and 2128. The liquid from the base of separator 2124 passes to water cooler 2132 and separator 2134 via conduits 2136 and 2138. The liquid from the base of separator 2134 passes to water cooler 2142 and separator 2144 via conduits 2146 and 2148. The liquid from the base of separator 2144 passes to water cooler 2152 and separator 2154 via conduits 2156 and 2158. The liquid from the base of separator 2154 passes to water cooler 2162 and separator 2164 via conduits 2166 and 2168. The liquid from the base of separator 2164 passes to water cooler 2172 and separator 2174 via conduits 2176 and 2178. The liquid from the base of separator 2174 passes to water cooler 2182 and separator 2184 via conduits 2186 and 2188. The liquid from the base of separator 2184 passes to water cooler 2192 and separator 2194 via conduits 2196 and 2198. The liquid from the base of separator 2194 passes to water cooler 2202 and separator 2204 via conduits 2206 and 2208. The liquid from the base of separator 2204 passes to water cooler 2212 and separator 2214 via conduits 2216 and 2218. The liquid from the base of separator 2214 passes to water cooler 2222 and separator 2224 via conduits 2226 and 2228. The liquid from the base of separator 2224 passes to water cooler 2232 and separator 2234 via conduits 2236 and 2238. The liquid from the base of separator 2234 passes to water cooler 2242 and separator 2244 via conduits 2246 and 2248. The liquid from the base of separator 2244 passes to water cooler 2252 and separator 2254 via conduits 2256 and 2258. The liquid from the base of separator 2254 passes to water cooler 2262 and separator 2264 via conduits 2266 and 2268. The liquid from the base of separator 2264 passes to water cooler 2272 and separator 2274 via conduits 2276 and 2278. The liquid from the base of separator 2274 passes to water cooler 2282 and separator 2284 via conduits 2286 and 2288. The liquid from the base of separator 2284 passes to water cooler 2292 and separator 2294 via conduits 2296 and

106 and 110. The condensed liquid is passed by gravity flow from separator 112 through conduit 114 into the middle of rectifying column 116. The reflux is provided in the rectifying column 116 by heating the calandria 142 with steam and cooling the condenser 144 with water. The stabilized gasoline produced at the base of the rectifying column 116 is removed from the system by way of conduit 146 and valve 148. The 5 non-condensable vapors leaving the top of rectifier 116 are passed to the second stage of the compressor 122 via conduit 120. The gaseous fractions from the separator 112 are combined with the non-condensable vapors from the rectifier 116 by introducing via conduit 118 into conduit 120. These combined vapors are compressed by compressor 122 to a pressure of about 10 atmospheres, cooled to room temperature by means of water cooler 126 and passed into rectifier 130 10 via conduits 124 and 128. Reflux is produced in rectifier 130 by heating calandria 132 with steam and cooling condenser 138 with water. The liquid from the base of rectifier 130 is expanded through valve 134 to 3 atmospheres pressure and conducted via conduit 136 to conduit 106 where it is mixed with the vapors leaving compressor 104. The non-condensable gas leaving the top of rectifier 130 is conducted via conduit 140 to the third 15 stage of the compressor 150 where it is compressed to 33 atmospheres. The thus compressed gas is then conducted by conduit 152 through water cooler 154 and conduit 156 into the rectifying column 158. Reflux liquids in rectifying column 158 are produced by heating calandria 160 with steam and cooling condenser 166 with water. The liquid from the base of rectifier 158 is expanded through expansion valve 162 to a pressure of 10 atmospheres and then via conduit 164 is introduced into 124 where it mixes with the 20 vapors leaving compressor 122. Non-condensable gas leaves the rectifier 158 via conduit 168, at the top thereof.

The process described herein is an improvement over the process described in the copending application Serial No. 30,031, of C. H. Greene-walt, in that the liquid in the process herein is essentially free of low boiling materials. It is therefore more advantageously employed as an absorption oil to promote the condensation of 25 high boiling components from the intermediate pressure gas.

Example

A gas of the following composition that had 30 been produced by the vapor phase cracking of petroleum was processed according to the modification of the invention as shown by Figure I.

	Mole per cent
60 Hydrogen	8
Methane	20
Ethylene	25
Ethane	10
Propylene and propane	17
C ₄ hydrocarbons	10
C ₅ and heavier hydrocarbons	10
	100

This gas was compressed to six atmospheres, 70 combined with the expanded liquid from the high pressure rectifier, cooled to 30° C., the liquid separated from the vapor and the liquid processed in the intermediate pressure rectifier. The base of this rectifier was heated with steam to 117° C., at which temperature essentially all of the butylene

and more volatile components were expelled from the liquid producing gasoline containing essentially only C₅ and heavier hydrocarbons. The condenser of the intermediate pressure rectifier was cooled to 30° C. The vent gas from this 5 rectifier was combined with the vapor from the separator and the mixture compressed to 34 atmospheres. The compressed gas fed directly to the middle of the high pressure distilling column, the base temperature of which was maintained at 155° C. The liquid remaining in the rectifier base at this temperature was continuously expanded to the intermediate pressure of six atmospheres and combined with the effluent from the first stage compressor. This liquid had 15 the following composition:

	Mole per cent
Propylene and propane	5
C ₄ hydrocarbons	26
C ₅ and heavier hydrocarbons	69 20
	100

The vapors leaving the top of the high pressure rectifier at 25° C. contained essentially all of the butylene and lighter components originally contained in the crude gas together with about 1/2 of 25 1 mole per cent of C₅ hydrocarbons.

It is desirable to heat the base of rectifiers 30 and 158 to such a temperature that essentially 30 all of the butylene and more volatile components are driven from the liquid. However, many crude gases contain such a quantity of polymer and gum-forming materials that this procedure is impractical. Under such a condition the base of rectifiers 30 or 158 may be heated to a temperature below that at which polymerization takes place allowing the liquid which is expanded from the base of this rectifier to contain appreciable quantities of butylene and propylene.

The compression system outlined in Figure I 40 contains only two stages. The compression system may contain three stages as shown by Figure II or even a larger number of stages may be used. In every case it is obvious additional rectifiers 45 will be required with the liquid from the highest pressure rectifier being expanded back into the discharge line from the next highest pressure compressor exactly as shown herein.

In my experiments I desired to produce a stabilized gasoline at the base of rectifiers 16 or 116 which was essentially free of butylene and more volatile components. In the gasoline industry it is oftentimes desirable to leave up to 5% of butylene in the liquid. This may be accomplished in the process herein described by reducing the temperature in calandrias 42 or 142 to say 100° instead of 115° as mentioned in the above example.

This process has the advantage of recycling a 60 minimum quantity of intermediate boiling material and thereby reducing the power used for operating the compressors. Also in the present invention no liquid or gaseous product attains a temperature lower than that of cooling water, thus eliminating troublesome freeze-ups that 65 might occur if temperatures are used below the freezing point of water, in view of the fact that the incoming gas contains a small amount of water. A further power savings is accomplished by expanding the high pressure liquid from the rectifier into the effluent from the next lower compressor. This liquid acts as an absorbing oil condensing from the effluent certain of the heavier fractions that would normally remain in the gas and be recompressed to the higher pressure.

As many apparently widely different embodiments of this invention may be made without departing from the spirit and scope thereof, it is to be understood that I do not limit myself to the 5 specific embodiments thereof except as defined in the appended patent claims.

I claim:

1. The process which comprises compressing a gaseous mixture from cracked petroleum hydro-
10 carbons containing a gasoline fraction and gases that are lower boiling than said gasoline fraction, cooling the compressed gases to effect liquefaction of said gasoline fraction, separating said gasoline fraction therefrom, rectifying the separated gasoline fraction by counter-current flow of reflux liquors and by boiling the liquid at the base of the rectifying column in order to establish refluxing conditions and expel the lower boiling hydrocarbons from the liquid gasoline,
15 20 combining the gaseous fraction obtained from the rectification step and the gaseous fraction obtained from the gas and liquid separation step, compressing said gaseous fraction in a plurality of compression stages, said stages being characterized in that there is a cooling and rectifying step between each stage of compression, said rectifying steps being operated by counter-current flow of refluxing liquors and by boiling the liquid at the base of the rectifying column in order
25 30 to establish refluxing conditions and separate as a liquid gasoline and expel the lower boiling hydrocarbons therefrom, said process being further characterized in that the gasoline fraction from the higher pressure stage is expanded to the pressure of the next lower pressure stage and combined with the effluent from the next lower pressure stage.
35

2. An apparatus for separating the components of a fluid mixture which comprises the following elements in combination: a gas and liquid separator and a multi-stage compressor, together with a cooler and a rectifier for each compression stage, means for introducing the fluid mixture into the first compression stage, means for passing the fluid mixture from the first compression stage through the cooler connected therewith into the gas and liquid separator, means for passing the liquid from the gas and liquid separator into the rectifying column adapted for operation with the first compression stage, means for withdrawing the gaseous fraction from the gas and liquid separator and the gaseous fraction from the rectifying column and combining same and introducing said combined gaseous fractions into the second compression stage, means for removing the liquid fraction from the bottom of the rectifying column; separate means for withdrawing the gases from the top of the rectifier in each compression stage except the first and last and introducing said gases into the next higher compression stage, separate means for passing the compressed gases from each compression stage above the first through the cooler for each compression stage into the rectifying column for each compression stage, separate means for withdrawing the gases from the rectifier of the last compression stage, 30 and separate means for withdrawing the liquid from each of the rectifying columns for each of the compression stages except the first and for combining said liquid with the effluent from the compression stage next lower in pressure. 35
